Julien A. Bried
INVENTOR

UNITED STATES PATENT OFFICE.

JULIEN A. BRIED, OF OAKLAND, CALIFORNIA.

ROLLING SCREEN.

1,395,475.

Specification of Letters Patent. Patented Nov. 1, 1921.

Application filed February 28, 1917. Serial No. 151,016.

To all whom it may concern:

Be it known that I, JULIEN A. BRIED, a citizen of the United States, residing at Oakland, in the county of Alameda and State of California, have invented a new and useful Improvement in Rolling Screens, of which the following is a specification and which is illustrated in the accompanying drawings.

10 My invention relates to the improvement in rolling screens as applied to windows and other openings for the keeping out of flies and insects, and has for its objects the production of a rolling screen of simple construction easy to install and which will be extraordinarily tightly stretched when in position over the window opening and also effectually sealed at the edges against the entrance of insects, without the necessity of 15 running the edges of the screen in a groove.

I attain the objects outlined above by the device illustrated in the drawings accompanying this specification in which Figure 1 is a perspective view of a window casing 25 as seen from the inside of a room and shows a rolling screen of my improved construction in position with the screen rolled up.

Fig. 2 is a larger view of a vertical cross section of the device with the screen pulled 30 down to cover the opening.

Fig. 3 is a cross section taken through the line *a*, *a* of Fig. 1 and shows the screen fabric seated at its edges and overhanging arched strips secured to the casing at both 35 sides.

Fig. 4 is a similar view to Fig. 3 and shows a variation in the form of the arched seating strips permitting a greater overhang of the screen edges with a given width 40 of fabric.

Fig. 5 is a view of the tension lever in locked position.

A clear understanding of the improvement embodied in my rolling screen will be 45 had upon a more detailed reference to the drawings as follows. In Fig. 1 the screen carrying roller 2 is shown positioned at the inside upper part of a window (the sheet metal dust casing 16 and the regular window shade roller 15 and its brackets 18 all 50 shown in Fig. 2 being omitted to show more clearly the novel features of my invention.)

The screen fabric 1 is attached by its upper edge to, and shown rolled up on, a spring 55 actuated roller 2. This roller is secured in place on the window casing by the brack-

ets 3, 3' and is a common spring shade roller (preferably of the metal variety) with the exception that it dispenses with the usual pawl (to hold a shade at various heights) 60 and has a gear wheel 4 secured to one end.

The brackets 3, 3' are similar to the ordinary shade roller supporting brackets adapted to rotatably support the roller and hold the rewinding spring at any desired 65 tension.

The screen fabric 1, which may be of light woven wire though I prefer a painted or water-proofed cotton cloth screen fabric on account of its greater flexibility, has a stick 70 5 attached to its lower end, with several metal eyelets depending therefrom adapted to engage with the sill plates 7 to securely hold it when the screen is pulled down.

After pulling down the screen and securing it in place the toggle tension lever 8 is pushed upward to force the short rack on the upper end of the rod 9 into engagement with the gear wheel 4 on the end of the roller to forcibly turn it and cause great 80 tension in the fabric, Fig. 5 showing the locked position of the tension lever 8 when pushed upward.

On each side of the window casing is secured a strip 10, preferably of wood, projecting a short distance from the surface of the window casing and against which strips the screen fabric rests when pulled down.

The strips 10 are sprung away from the surface of the window casing in the center before securing them firmly in place so as to form convexly arched seats; as clearly shown at 12 in Figs. 1 and 2; and against which the screen fabric tightly seats itself along both edges when forcibly stretched 95 with the tension device as described.

The screen fabric would seat itself against the arched strips through the screen tension produced by the action of the spring roller alone, but the tension of the ordinary spring roller would not cause as snug a seat on the strips as the very great tension produced by the rack and pinion device shown. In fact with this or a similar tensioning device the roller need not be spring actuated at all in 100 so far as this feature of my invention is concerned and the fabric could be rewound by any other desired means.

To assist in making an insect tight joint along the edges when the screen is pulled 110 down, I also allow the fabric to overhang the arched strips as shown in Figs. 3 and 4 at

11, the greater overhang shown in Fig. 4 being due to the seating portion of the strips being placed farther inward from the edge of the window casing.

5 The strips 10 instead of being sprung to an arched condition and nailed to the edge of the window casing, may if desired be formed to the required curve and attached to the face of the casing at the edge of the 10 window opening, but the method described of springing the strips to the arched form is simpler.

At the upper edge of the window opening is secured another strip 13 in Figs. 1 and 2. 15 This strip projects sufficiently to allow for the thickness of fabric when rolled up on the roller and provides a seat against which a portion of the fabric bears across the width of the window opening at the top 20 when the screen is pulled down and forms an insect seal across the top of the window opening.

The lower ends of both arched strips are notched at 14 Figs. 1 and 2, one half the 25 thickness of the stick 5 attached to the lower end of the screen, to allow the fabric to come in contact with the strips just above that point.

Fig. 2 is a vertical cross section of the 30 screen when pulled down and shows the position of the screen roller in relation to the standard shade roller, the latter being shown at 15 and it will be observed that my screen fabric sheet 1 pulls down between the 35 regular shade roller 15 and the window casing and is also narrow enough to come down between the end brackets 18 ordinarily used to support the shade roller. At 16 in the same figure is shown in cross section a metal 40 protective casing almost surrounding the roller screen to protect it against dust when rolled up; the dust casing may be supported on the end brackets 3, 3', or on the window casing or both. At 17 is indicated the actuating or rewinding spring within the screen 45 roller 2, but no importance attaches to any particular construction of this feature, for any common spring shade roller may be used.

It might be mentioned at this point that 50 if desired my screen can easily be adapted to cover but part of the window opening by arranging a stop piece across the opening at the desired point and securing the stick 5 at the lower end of the screen to the stop 55 piece instead of to the stick.

Having thus described my invention it will be seen that I have provided a rolling window screen of simple construction which is sealed at the edges by seating itself tightly 60 against arched strips attached to the window casing and is easily applied to the inside of a window casing just above and without interference with the regular shade roller and also, that while I have shown and described a tensioning device which acts on the 65

roller to forcibly twist it to produce the tension, any other means to obtain a greater tension in the fabric than normally produced by the rewinding spring in the roller may be used and still come within the scope of 70 my invention, as for instance the locking of the roller against further rotation after pulling the screen almost down, then forcing the lower end of the screen the balance of the way down by any suitable lever arrangement operating on the lower stick 5, and although I prefer the rack and pinion device acting on the roller as shown in the drawing I feel entitled to cover in my claims any method of manually and forcibly tensioning 80 a roller screen apart from a spring within the roller and also an arched or curved seat at the edges of an opening used with any kind of a screen whether on a roller or simply stretched over the opening, and likewise 85 these principles if applied to shades instead of screens as I believe them to be new and useful in either connection.

I claim:—

1. In a window screen or shade, strips 90 secured at the edges of a window opening and convexly curved in direction of their length, a fabric sheet tensioned over the opening and seated against the convex surface of said strips. 95

2. In a fabric sheet screen or shade adapted to screen or shade an opening, strips secured to opposite side edges of the opening to be screened or shaded and against which strips the fabric sheet is adapted to seat at 100 its edges when tensioned over the opening, a portion of the seating surfaces of said strips being slightly displaced from the normal plane of the main portion of the fabric sheet covering the opening to effect a tight seat with the edges of said fabric sheet. 105

3. A roller window screen or shade comprising a roller adapted to be rotatably secured at one end of an opening to be screened or shaded, a fabric sheet secured at one edge 110 to the roller, means for removably securing the opposite edge of the sheet to the opposite edge of the opening and manually operated means for forcibly rotating the roller to rewind the fabric sheet slightly upon the 115 roller to produce a tension in said fabric sheet and for locking the roller in such rewound position, said means being out of operative engagement with the roller when the screen is being raised or lowered. 120

4. In a roller window screen, a spring actuated roller adapted to be rotatably secured at one end of a window opening, a screen fabric sheet secured at one end to said roller, means for detachably securing the 125 free end of the screen at the other end of the opening, strips convexly curved in direction of their length, secured to the side edges of the opening and against the convexly curved surfaces of which strips the 130

- screen fabric is adapted to seat near its side edges when unrolled and held in tension over said opening.
5. In a roller window screen or shade, a roller adapted to be rotatably secured at one end of a window opening, a fabric sheet secured at one end to said roller, means for detachably securing the other end of the fabric sheet at the opposite end of the opening, means for rolling the fabric sheet upon said roller, means for producing a tension in said fabric sheet, strips secured to opposite side edges of the opening and against which strips the fabric sheet is adapted to seat near its edges when unrolled over the opening, a portion of the seating surfaces of said strips being slightly displaced from a plane which that portion of the fabric sheet covering the opening would otherwise assume when tensioned over the opening.
10. In a roller window screen or shade, a roller adapted to be rotatably secured at one end of a window opening, a fabric sheet secured at one end to said roller, means for detachably securing the other end of the fabric sheet at the opposite end of the opening, means for rolling the fabric sheet upon said roller, means for producing a tension in said fabric sheet, strips secured to opposite side edges of the opening and against which strips the fabric sheet is adapted to seat near its edges and overlap when unrolled over the opening, a portion of the seating surfaces of said strips being slightly displaced from a plane which that portion of the fabric sheet covering the opening would otherwise assume when tensioned over the opening.
15. 7. A roller window screen or shade comprising a spring actuated roller adapted to be rotatably secured at one end of an opening to be screened or shaded, a fabric sheet secured at one end to said roller, a stiffening member secured to the other end of said fabric sheet, means for removably securing the stiffening member at the opposite end of the opening and manually operated means for forcibly rotating the roller slightly to produce a tension in said fabric sheet greater than the tension normally produced therein by the rewinding action of the actuating spring, said means being out of operative engagement with the roller when the screen is being raised or lowered.
20. 8. A roller window screen or shade comprising a spring actuated roller adapted to be rotatably secured at one end of an opening to be screened or shaded, a fabric sheet secured at one end to said roller, a stiffening member secured to the other end of said fabric sheet, means for removably securing the stiffening member at the opposite end of the opening, and strips slightly convexly curved in direction of their length secured to the side edges of the opening, against the curved surfaces of which strips the fabric sheet is adapted to seat near its side edges when tensioned over the opening and manually operated means for forcibly turning the roller for rewinding the fabric sheet slightly upon the roller to increase the tension in said fabric sheet and for locking the roller against reverse turning.
25. 9. In a roller window screen or shade, a spring actuated roller adapted to be rotatably secured at one end of a window opening, a toothed wheel secured to one end of said roller, a fabric sheet secured at one end to said roller, a stiffening member secured to the other end of the fabric sheet, means for removably securing said stiffening member to the opposite end of the window opening, a rack bar movably secured at the side of the window opening adapted to engage said toothed wheel and means for manually operating said rack bar.
30. 10. In a roller window screen or shade, a spring actuated roller adapted to be rotatably secured at one end of a window opening, a toothed wheel secured to one end of said roller, a fabric sheet secured at one end to said roller, a stiffening member secured to the other end of the fabric sheet, means for removably securing said stiffening member to the opposite end of the window opening, a lever controlled rack bar operatively secured at the side of the window opening and adapted to engage said toothed wheel and to rotate said roller slightly upon the operation of said lever, to increase the tension in said fabric sheet, said lever being adapted to lock the rack bar to prevent reverse rotation of said roller.
35. 11. In a roller window screen, a screen fabric carrying roller rotatably secured to the face of a window casing above the end of a window opening, a seating strip to form an insect seal secured at the upper end of said opening to the edge of said window casing and projecting sufficiently beyond the face of said window casing to touch the fabric sheet when same is unrolled and drawn over the opening.
